COMBINED ROTISSERIE OVEN AND FOOD WARMER

Charles M. Vaughan, 28 Frontus St., Greenville, S.C.

Continuation of design application Ser. No. 68,823,
Feb. 14, 1962. This application June 4, 1964, Ser. No.
80,474

Term of patent 14 years

(Cl. D81—10)

Fig. 1.

Fig. 2.

Fig. 3

FIGURE 1 is a front perspective view of a combined rotisserie oven and food warmer embodying my new design;

FIGURE 2 is a rear perspective view thereof; and

FIGURE 3 is a fragmentary front perspective view thereof.

The dominant features of my design reside in the portion shown in full lines wherein the design is characterized by the combination of the slanted control panel, the relatively narrow elongated window thereabove and the relatively narrow elongated panel disposed therebetween on the front side of the combined rotisserie oven and food warmer.

This application is a continuation of my earlier filed pending application Serial No. D. 68,823, filed February 14, 1962, and now abandoned.

I claim:

The ornamental design for a combined rotisserie oven and food warmer, substantially as shown and described.
